UNITED STATES PATENT OFFICE

WILLIAM G. HARTWIG, OF CHICAGO, ILLINOIS, ASSIGNOR TO RAILWAY UTILITY COMPANY, OF CHICAGO, ILLINOIS, A CORPORATION OF ILLINOIS

HEATING SYSTEM FOR RAILWAY CARS AND THE LIKE

Application filed January 23, 1932. Serial No. 588,293.

My invention relates to the control of heating systems, more particularly electric heating systems such as commonly used in street and other railway cars, though it may be applied for the control of systems employing other heating media, as for example, steam.

My improved system is of the well known type in which an electromagnetic main switch, controlling the supply of heating medium to the heater is controlled by a relay, which in turn is controlled by a thermostat. It is important with respect to the relay, and more particularly with respect to the thermostat to reduce as far as possible sparking and the flow of excess current, particularly on the opening of the circuit. It is also important to provide against excess current through the controlling instrumentalities in case of the grounding of the coil of a main switch or contactor. A further circumstance which must be guarded against so far as practicable is the tampering with the apparatus particularly by the car crew. In prior wiring of such systems, the cutting of the wires leading to the thermostat leaves the contactor circuit and consequently the heating circuit closed and therefore it has been not uncommon for a member of the crew of a car to cut the wires beneath the thermostat so as to keep the car at a higher temperature. It is the object of the present invention to minimize the above mentioned objections to systems of this character.

In the accompanying drawing I have shown diagrammatically the improved circuit of my invention.

In the drawing the line from which the supply of electric current is derived is indicated at 1, the contactor or main switch at 2, and the heater supplied from the line at 3. These elements of the system may be of any desired or approved type. The coil of the contactor is indicated at 4 and it is supplied with current from the line through a line resistor 5, wiring 6, movable and stationary contacts 7, 8 and wire 9. The other end of the coil 4 is grounded through wire 10, a balance resistance 11 and wires 12, 13. A shunt circuit about the coil 4 is provided, the shunt being controlled by a switch, the contacts of which

are closed prior to the separation of the contacts 7, 8 to open the circuit of the contactor coil 4, and remain closed until the closing of the contacts 7, 8. Both these pairs of contacts, to-wit, those controlling the contactor coil circuit and those controlling the shunt are controlled by a relay coil 14, which in turn is controlled by the thermostat. In the specific embodiment of the invention illustrated, one of the contacts 15 of the shunt is formed with the movable contact 7 of the contactor coil circuit, the two contacts 7, 15 forming with their barrel or hinge member 16 a pivoted or swinging element which is electrically connected to wire 6, above mentioned. The other contact of the pair controlling the shunt circuit is the pivoted armature 17 of the relay. When the relay coil 14 is deenergized the armature and the swinging element, above described, occupy the position shown in the drawing in which contact 7 is engaged with contact 8 and the contactor coil is supplied with energizing current. At the same time the armature 17 is out of engagement with contact 15. When the relay coil 14 is energized, it, of course, attracts its armature 17 which first engages contact 15, thus closing the shunt circuit. The further movement of armature 17 under the attraction of the relay coil separates contacts 7 and 8 and thus de-energizes the contactor coil. Preferably, the armature 17 is provided with an insulated angular member 18 which, when the armature drops, engages the upper face of contact member 15 so that the weight of the armature serves to firmly hold the contact 7 in engagement with fixed contact 8.

The shunt circuit about coil 4 is completed to the balance resistance by the wire 19. Thus when the shunt contacts are in engagement a path for the current is created from wire 6 through contact 15, armature contact 17, wire 19, balance resistance 11, wire 12 and wire 13 to ground.

One terminal of the relay coil 14 is connected by wire 21 to the end of the balance resistance adjacent the contacts just described. The other end of the relay coil is connected through wire 22, fuse 23 and test key 24 to the upper contact 25 of the thermo-

stat. The lower thermostat contact 26 is connected to the ground wire 13 above mentioned. The relay coil is thus in parallel to the balance resistance, and when the temperature rises to the point for which the thermostat is designed, a branch or shunt circuit through the relay coil is provided as follows: Through wire 21, relay coil 14, wire 22, fuse 23, test key 24, the thermostat and to ground through wire 13:

In order to reduce the current through the thermostat, particularly at the time it opens its circuit and at the same time to assure the feeble current in the relay coil required to hold the relay after it has been raised to its attracted position, I provide a shunt circuit 35 containing a relatively low resistance 36 about the point of union of the relay coil circuit with the main switch and main shunt circuits. Shunt 35 is connected to wire 12 at one end and at the other is provided with a contact 37 arranged to be engaged by contact 7 as the armature 17 approaches its attracted position. Thus the main portion of the current which energized relay coil 14 to cause it to attract its armature is diverted through shunt circuit 35, so that only a feeble current is flowing through the thermostat at the time it breaks the circuit.

While I have shown and described a thermometer type thermostat it will be obvious that a bi-metallic or other thermostat may be used. As an instance of a suitable proportioning of the resistances of the several circuits of the system, the contactor or main switch may have a resistance of 840 ohms, the balance resistance, 225 ohms, the relay coil circuit 1200 ohms and coil 36, 50 ohms.

It will be noted that the thermostat and the main switch or contactor coil are grounded by the same wire 13 from which it follows that if both wires connected to the respective contacts of the thermostat are cut, or if the ground wire is cut, the contactor coil as well as the relay coil is deenergized so that the heating circuit remains open. Ordinarily the wires connected to the contacts of thermostats of this character are carried together through the back or support of the thermostat and through a panel or other part of the wall of the car so that they are conveniently accessible only between the back of the thermostat and the supporting surface of the wall and consequently it is at this point that they are ordinarily tampered with. Therefore, the effort by anyone unskilled in the wiring, such as a member of the car crew, to dismantle the control by cutting the wires results in throwing off the heat altogether until the apparatus is repaired.

Furthermore, a grounding or short-circuiting or an opening of the coil 4 similarly affects the circuit through the relay coil and thermostat so that the latter are not subjected to injuriously heavy current in any such

event. It is also to be observed that sparking between the contacts 7 and 8 upon their opening is avoided by the previous establishment of the shunt circuit.

I claim:

1. In a system for controlling the flow of heating medium to a heater, an automatic, electromagnetic switch comprising an operating coil, a shunt circuit about said coil, a source of electric energy, connections therefrom to said coil and shunt circuit, a pair of contacts in the coil circuit, a pair of contacts in the shunt circuit, connections between movable members of said pairs of contacts whereby one pair is open when the other is closed, a relay coil in series with both the operating coil and the shunt circuit for opening and closing said pairs of contacts, and a thermostat in series with said relay coil for controlling current flow therethrough.

2. In a system for controlling the flow of heating medium to a heater, an automatic, electromagnetic switch, comprising an operating coil, a shunt circuit about said coil, a source of electrical energy, connections therefrom to said coil and shunt circuit, a pair of contacts in the circuit of said coil, a pair of contacts in said shunt circuit, connections between movable members of said pairs of contacts whereby one pair is open when the other is closed, a relay coil in series with both the operating coil and shunt circuit for opening and closing said pairs of contacts, a thermostat in series with said relay coil for controlling current flow therethrough, and a shunt circuit about said relay coil and thermostat.

3. In a system for controlling the flow of heating medium to a heater, an automatic, electromagnetic switch, comprising an operating coil, a shunt circuit about said coil, a source of electrical energy connections therefrom to said coil and shunt circuit, a pair of contacts in the circuit of said coil, a pair of contacts in said shunt circuit, connections between movable members of said pairs of contacts whereby one pair is open when the other is closed, a relay coil in series with both the operating coil and shunt circuit for opening and closing said pairs of contacts, a thermostat in series with said relay coil for controlling current flow therethrough, and a shunt circuit about said relay coil and thermostat including a balance resistor.

4. In a system for controlling the flow of heating medium to a heater, an automatic, electromagnetic switch comprising an operating coil, a shunt circuit about said coil, means for opening and closing said coil and shunt circuits, comprising a movable member common to both said circuits and a second movable member adapted to engage the first to close the shunt circuit and operate said first movable member to open the coil circuit, a source of electric energy, connec-

5 tions therefrom to the first said movable member, a relay coil for operating the second movable member, in series with both said circuits, and a thermostat in series with said relay coil and controlling the flow of current therethrough.

10 5. In a system for controlling the flow of heating medium to a heater, an automatic, electromagnetic switch comprising an operating coil, a shunt circuit about said coil, means for opening and closing the coil and shunt circuits, comprising a movable member common to both said circuits and a second movable member adapted to engage the first to close the shunt circuit and operate said first movable member to open the coil circuit, a source of electric energy, connections therefrom to the first said movable member, a relay coil for operating the second said movable member, in series with both said circuits, a thermostat in series with said relay coil and controlling the flow of current therethrough, and a second circuit parallel to the circuit through said relay coil and thermostat and containing a balance resistor.

20 6. A system for controlling the flow of heating medium to a heater as described in claim 5 in which the shunt circuit about the operating coil is closed before the operating coil circuit is opened.

25 7. In a system for controlling the flow of heating medium to a heater, an automatic, electromagnetic switch comprising an operating coil, a shunt circuit about said coil, means for opening and closing said coil and shunt circuit, comprising a movable member common to both said circuits and a second movable member adapted to engage the first to close the shunt circuit and operate said first movable member to open the coil circuit, a source of electric energy, connections therefrom to the first said movable member, a relay coil for operating the second movable member, in series with both said circuits, a thermostat in series with said relay coil and controlling the flow of current therethrough, a low resistance shunt circuit about the thermostat and relay coil, and means for closing said shunt circuit after the relay and thermostat circuit is closed and maintaining it closed until after the thermostat opens said relay coil circuit.

30 8. In a system for controlling the flow of heating medium to a heater, an automatic, electromagnetic switch comprising an operating coil, a shunt circuit about said coil, a fixed contact for said coil circuit, a movable contact for the coil circuit, a source of electric energy, connections therefrom to said movable contact, a relay comprising a coil and an armature, the armature adapted when the coil is energized to engage said movable contact and first close the shunt circuit and then move said contact to open the coil circuit, the coil of the relay being in

series both with the coil circuit and the shunt circuit, and a thermostat controlling the circuit of said relay coil.

35 9. In a system for controlling the flow of heating medium to a heater, an automatic, electromagnetic switch comprising an operating coil, a shunt circuit about said coil, a relay the coil of which is in series to both the coil circuit and the shunt circuit, a thermostat in the relay coil circuit, a low resistance shunt circuit about the relay coil and thermostat, a movable contact member, a source of electric energy and connections therefrom to said movable contact member, a relatively fixed contact with which the movable contact engages to close the circuit through the first mentioned coil, a second relatively fixed contact with which said movable contact engages to close the low resistance circuit about the relay coil and thermostat, and an armature for the relay coil adapted to engage said movable contact and thereby first close the first mentioned shunt circuit and thereafter open said coil circuit and close the shunt circuit about the relay coil and thermostat.

40 In testimony whereof, I have subscribed my name.
